CLAIM

The ornamental design for a connector cap for tubes, as shown and described.

DESCRIPTION

FIG. 1 is a top perspective view of a connector cap for tubes according to the present invention.

FIG. 2 is a top view of the connector cap for tubes of FIG. 1.

FIG. 3 is a bottom view of the connector cap for tubes of FIG. 1.

FIG. 4 is a front side view of the connector cap for tubes of FIG. 1.

FIG. 5 is a back side view of the connector cap for tubes of FIG. 1.

FIG. 6 is a left side view of the connector cap for tubes of FIG. 1.

FIG. 7 is a right side view of the connector cap for tubes of FIG. 1; and,

FIG. 8 is a bottom perspective view of the connector cap for tubes of FIG. 1.

The portions of the drawings shown in dashed lines are for environment only and do not form a part of the claimed design.

1 Claim, 5 Drawing Sheets(56)
